RADIO CONTROL SYSTEM

Erick B. Berglund, Garden City, N. Y., assignor to
 Radio Corporation of America, a corporation
 of Delaware

Application August 30, 1941, Serial No. 409,005

5 Claims. (Cl. 179—1)

The present invention relates to the control of, and mixing of, a plurality of different audio frequency currents and, more particularly, to radio broadcasting wherein a radio wave is modulated in accordance with the currents from a plurality of separate microphone circuits.

In broadcasting certain types of programs such as, for example, speeches in a foreign language, sports events, etc., it is sometimes desirable for an interpreter or a commentator to interpolate an interpretation or comment the main program during the time when it is being presented. In accordance with the present invention the interpreter, or commentator, operates a key switch fading the main program to an unobtrusive level and simultaneously cutting in his own microphone. During the time the interpolations are heard the main program may be heard in the background. After the comments are completed release of the key switch restores the main program to full volume level at a predetermined rate. The fading rate of the main program and its recovery time is controllable so that the switching is not disagreeably noticed by the listening audience.

An object of the present invention is the provision of a circuit arrangement for readily performing the above mentioned operations.

Another object of the present invention is the provision of an arrangement, as aforesaid, which is positively under the control of the interpreter, or commentator, at all times.

Still another object is the provision of means for smoothly varying the level in a signal channel from one predetermined limit to another.

Still a further object of the present invention is the interpolation of one signal into another signal without causing disturbing noises.

The present invention will be more fully understood by reference to the following detailed description which is accompanied by drawings in which Figure 1 illustrates, partly in schematic circuit form and, partly in conventional block diagram form, an embodiment of the present invention, and Figure 2 is a curve illustrating the variations in the different signal levels in the output of the device of Figure 1.

Referring, now, to Figure 1, there is shown at 10 an input transformer or coupling means for coupling a program circuit to a first amplifier tube 11. The program circuit which may be extended from a point remote from the usual broadcast studios is, under such circumstances, commonly known as a "nemo" circuit and the input is, therefore, labelled "nemo input." Tube 11,

which is shown as a triode connected pentode tube, may be a triode or it may be operated as a pentode amplifier as circumstances require. A volume control 12 in the grid circuit of tube 11 is provided to compensate for variations in level of the input signal. Tube 11 is shown as having its grid biased by means of a cathode resistor 13 and a by-pass condenser 14 though, of course, a grid bias battery may be used instead, if desired. Between the anode of tube 11 and the positive anode supply source B+, is connected a plate load resistor 15. Coupled to the anode end of resistor 15 by means of condenser 16 is the control grid circuit of a super control pentode amplifier tube 17. This tube is used because of the fact that control grid bias variation is capable of varying the amplification thereof over a wide range. The anode of tube 17 is connected to the positive anode supply source B+, through output transformer 18. Output transformer 18 is coupled through fader 31 to the input of amplifier 34. The output of amplifier 34 is coupled by conventional circuit means to the desired modulating equipment for modulating the broadcast radio wave.

The screen potential for tube 17 is supplied by a voltage divider composed of resistors 19 and 20 connected across the anode supply source. A standing bias is applied to tube 17 by means of cathode resistor 21. In the grid circuit of tube 17 are serially connected resistor 22 and condenser 23. To the junction between resistor 22 and condenser 23 is connected a resistor 24, the other end of which is connected to contacts 25 of relay 26. Contacts 25 are arranged to selectively connect resistor 24 to B— or ground through variable resistor 27 or through a selected portion of battery 28. The positive pole of battery 28 is grounded and by means of selector switch 29 different values of negative potential may be connected to relay contacts 25.

Relay 26, in addition to operating contacts 25, operates contacts 35 which are connected in a channel 30 to complete the channel circuit when relay 26 is operated. Channel 30 at its input is coupled to a microphone circuit for the use of the interpreter or commentator and at its output end is coupled through fader 33 to amplifier 34. The winding of relay 26 is energized from battery 36 whenever key 37 is operated. A cable is indicated in the circuit between key 37 and the remainder of the energizing circuit for relay 26 in order to indicate that the key 37 may be placed at any required distance from the remainder of the circuit. Usually, key 37 will be

located on the desk of the commentator or interpreter whose comments are to be interpolated into the program carried by the "nemo" channel. Resistors 41 and 42 are connected across the contacts 35 in order to prevent disturbing 5 clicks when the contacts are opened or closed.

In the operation of the circuit as described, when the key switch 37 is in the open or foreign position, relay 26 disconnects the interpolator channel 30 through the opening of contacts 35 and connects the junction between resistor 22 and condenser 23 to ground through resistors 24 and 27. The amplifier tube 17 thus operates at its standing bias value determined by resistor 21 and the "nemo" program is fed through amplifier tube 11, tube 17 through transformer 18, fader 31 into the input of amplifier 34 and thence out to its ultimate destination. Tube 17, as mentioned, operates as a normal amplifier with normal bias on its grid. When the key switch 37 is closed to its interpolation position, relay 26 is energized thus closing contacts 35 completing the interpolator channel 30 and applying a large negative bias from battery 28 to the junction between resistor 22 and condenser 23 and therefore to the control grid of tube 17. This fades the level of the "nemo" program a definite lower value depending upon the amount of bias applied to the grid of tube 17 by means of selector switch 29. The time required for the fade to become completely effective depends upon the time constant of resistor 24 and condenser 23. Ordinarily, this is adjusted to be of the order of a half second. The interpolator channel 30 being completed, the voice of the interpreter is applied at a full level determined by fader 33 to amplifier 34 and the foreign program is transmitted at a reduced level through fader 31 to amplifier 34. After the interpreter, or commentator, has finished his comments, key switch 37 is released and the interpolator channel 30 is immediately disconnected. The de-energization of relay 26 operates contacts 25 to a series circuit comprising resistors 24 and 27 across condenser 23. The time constant of the circuit including resistors 24 and 27 across condenser 23 determines the time of recovery of the amplifier tube 17 to its normal gain value. The time delay is variable between one-half and two seconds by varying the value of variable resistor 27.

Figure 2 illustrates in curve form the relationship between the volume levels of the "nemo" program and the interpolator program at the inputs of faders 31 and 33 before, during and after actuation of key switch 37. In part 1, when the key switch is open, it will be noted that the "nemo" output indicated by solid line 45 is adjusted to a level of -16 VU by fader 31. The output of the interpolator channel is absent since its circuit is open. At the end of part 1 the key switch 37 is operated and the interpolator output, as indicated by dotted line 46, instantaneously rises to the same level as that of the "nemo" output, that is, -16 VU. In the first one-half second following the operation of key switch 37 the "nemo" output level drops to a predetermined value which may be either 13, 18 or 23 db. below the normal level, depending upon the position of switch 29. This relationship is maintained during the entire period during which key 37 is closed. At the end of part 2, the key switch 37 is opened and the output of the interpolator channel 30 immediately drops to zero. Due to the time constant of the combination of resistors 24 and 27 and condenser 23, the gain 75

of amplifier 17 is gradually restored so that the "nemo" output again attains its normal value of -16 VU. In Figure 2 this time period is labeled part 3 and, as indicated, may be adjusted to any value between one-half second and two seconds.

With the nemo amplifier output and the interpolator output directly under the control of the commentator or interpreter by means of key switch 37 the interpolation of comments and the fading of the nemo program can be perfectly synchronized without the difficulties encountered where the channel switching and fading is under the control of an engineer operating in response to cues or signals from the commentator. This is especially true in the case of unrehearsed foreign programs.

While I have particularly shown and described several embodiments of my invention, it is to be clearly understood that my invention is not limited thereto but that modifications may be made within the scope of the invention.

I claim:

1. In combination, a pair of channels for audio frequency currents, means for combining said channels into a single output circuit, an amplifier in one of said channels, the other of said channels being adapted to be connected to a microphone and having a normally open switch therein, and means at the location of said microphone and subject to manual control by a speaker for simultaneously operating said switch to complete said other channel and for gradually decreasing the gain of said amplifier to a predetermined level, said means, upon release, opening said switch and gradually restoring the gain of said amplifier, the rate of said restoration being substantially less than the rate of said decrease.

2. In combination, a pair of channels for audio frequency currents, means for combining said channels into a single output circuit, transducer means in one of said channels, the other of said channels being adapted to be connected to a microphone and being normally discontinuous, means at the location of said microphone and subject to manual control by a speaker for simultaneously establishing continuity in said other channel and for gradually decreasing the effectiveness of said transducer means to a predetermined level, said means being further operative to restore discontinuity to said other channel and to gradually restore the effectiveness of said transducer means and further means for controlling the rate of said restoration.

3. In combination, a pair of channels for audio frequency currents, means for combining said channels into a single output circuit, an amplifier tube in one of said channels, said amplifier tube having a standing bias on a control electrode thereof, the other of said channels being adapted to be connected to a microphone and having a normally open switch therein, and means at the location of said microphone and subject to manual control by a speaker for simultaneously operating said switch to complete said other channel and for gradually increasing said bias on said tube to reduce the gain thereof to a predetermined level, said means, upon release, opening said switch and gradually decreasing the bias on said tube to its standing value.

4. In combination, a pair of channels for audio frequency currents, means for combining said channels into a single output circuit, an amplifier in one of said channels, the other of said channels being adapted to be connected to a micro-

phone and having a normally open switch there-in, means at the location of said microphone and subject to manual control by a speaker for simultaneously operating said switch to complete said other channel and gradually decreasing the gain of said amplifier to a predetermined level, said means, upon release, opening said switch and gradually restoring the gain of said amplifier and further means for controlling the rate of said restoration.

5. In combination, a pair of channels for audio frequency currents, means for combining said channels into a single output circuit, means in said channels for controlling the transmission

of said currents therethrough, one of said channels being adapted to be connected to a microphone and being normally discontinuous and the other continuous, means at the location of said microphone and subject to manual control by a speaker for simultaneously establishing continuity in said one channel and gradually decreasing the transmission of said currents through said other channel to a predetermined level, said 10 means being further operative to again establish discontinuity to said one channel and to gradually restore the transmission to said other channel.

ERICK B. BERGLUND.
